UNITED STATES PATENT OFFICE.

EDWARD NIESEN, OF IRON MOUNTAIN, MISSOURI.

TABLE.

1,419,978.

Specification of Letters Patent. Patented June 20, 1922.

Application filed April 7, 1921. Serial No. 459,298.

To all whom it may concern:

Be it known that I, EDWARD NIESEN, a citizen of the United States, residing at Iron Mountain, in the county of St. Francois and 5 State of Missouri, have invented certain new and useful Improvements in Tables, of which the following is a specification.

This invention relates to improvements in folding tables and its prime object is to provide a table of this type that in assembled 10 position is spacious, stable and efficient and that when folded is compact and that can be stored or packed for shipping in minimum space. A further object is to provide a table 15 of this type that is of simple construction and consequently cheap to manufacture.

With the foregoing and other objects in view the invention consists in the combination and arrangement of parts to be herein- 20 after fully described, pointed out in the appended claim and illustrated in the accompanying drawings which form a part of this application and in which—

Fig. 1 is a vertical sectional view of my 25 improved table in elevation, assembled.

Fig. 2 is an inverted plan view of the table folded, one of the drawers being shown extended in dotted lines.

Fig. 3 is a view in elevation of the table 30 folded.

Fig. 4 is an inverted plan view of the leg and feet.

Fig. 5 is a section taken on line 5—5 of 35 Fig. 1.

Like reference characters denote corresponding parts throughout the several views. My table comprises the top formed of the sections 1, 2, one of which is provided with the channel bars 3 in which the rails 4 are 40 slidably disposed that are carried by the other top section, this arrangement permitting relative adjustment of the top sections in a well known manner thus forming an extension table top. Extra leaves can be inserted between the top sections when in their 45 extended position.

Pivotedly secured to the under surface of the top sections are the drawers 5 which may be swung outwardly, as shown in Fig. 2 in 50 dotted lines, to receive table accessories and then swung back beneath the top. A block 6 secured to the channel bars 3 is perforated to receive a screw-bolt 7 which extends through a perforated cap 8 which cap is secured to the said block 6. An oblong box 9 55 is provided with a threaded metal bearing 10

in its base to receive the screw-bolt 7 whereby said box is releasably secured in inverted position to the under side of the table top. The sides of the box 9 are formed with the 60 aligned elongated slots 11.

The leg 12 upon which the table top and connections are supported is formed in one end with a threaded bore to receive the screw-bolt 7 and it is formed also with the 65 pin-sockets 12^a to receive the pins 12^b and with the elongated recesses 13 thus forming the rib 14 which is formed with the transverse perforation 15 to receive the screw-bolt 7 when the same is withdrawn from the 70 terminal socket of said leg. Feet 16 pivoted in the recessed portions of the leg 12 extend, in operative position, outwardly from the leg and rest upon the floor to steady the leg, 75 said feet being notched adjacent their pivoted ends to receive the ring 17 that encircles the leg and is slidable thereover. When the table is in assembled position the threaded bore thereof receives the screw-bolt 7, the pins 12^b extend through the box slots 11 into 80 the leg sockets 12^a, the feet 16 have their free ends disposed upon the floor or table-supporting surface and the ring 17 retains the feet against play.

To fold the table the ring 17 is moved 85 over the leg away from the feet until it is clear of the recesses 13, the feet are then moved upon their pivots until they lie wholly within said recesses and the ring then moved back about the recessed leg portions 90 to encompass the feet and retain them in folded or inoperative position. The leg is now unscrewed from the bolt 7 together with the box 9, the pins removed from the leg bores 12^a and the leg disposed within the 95 box lengthwise of the same in such position that the screw-bolt will pass through the slots 11 and perforation 15. Pins 12^b are now again placed in the box slots 11 and pin sockets 12^a as shown in Fig. 2. 100

What is claimed is:—

In a table, a top, a screw-bolt carried by said top, a longitudinally slotted box releasably carried by said screw-bolt, a recessed and perforated leg, capable of disposal wholly 105 within said box, formed with a terminal bore to receive said screw-bolt and provided with pin sockets, pins releasably connecting the slotted portions of said box and the pin sockets of said leg, notched folding feet pivoted in the recessed portions of said leg, and a ring slidable over the recessed portions of 110

said leg for engagement with the notched portions of said feet in the extended position of the latter and adapted to encompass said feet in their folded position, the bore in
5 said leg being adapted to receive the said screw-bolt when said leg is in inoperative position and wholly disposed within said box.

In testimony that I claim the foregoing as my own I have hereto affixed my signature in the presence of two subscribing witnesses. 10
ED. NIESEN.
